UNITED STATES PATENT OFFICE

OTTO SCHAUMBERG, OF PITTSBURGH, PENNSYLVANIA, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA

TRANSFORMER.

1,034,934.

Specification of Letters Patent.

Patented Aug. 6, 1912.

Application filed July 8, 1908. Serial No. 442,223.

To all whom it may concern:

Be it known that I, OTTO SCHAUMBERG, a citizen of the United States, and a resident of Pittsburgh, in the county of Allegheny and State of Pennsylvania, have invented a new and useful Improvement in Transformers, of which the following is a specification.

My invention relates to alternating current transformers and inclosing casings therefor, and it has for its object to provide a simple and efficient means for clamping together the plates or laminæ of which the core structure is composed and other adjustable means coöperating therewith for securing the transformer within the casing.

My invention is specially adapted for use in connection with transformers provided with approximately cylindrical windings having their axes horizontally disposed and both horizontally and vertically disposed core sections, an inclosing tank or casing being provided which is adapted to receive such transformers, and special end frames and holding-in devices being also provided for holding the transformer core sections firmly together and for firmly securing them to the casing after the transformer is assembled and disposed therein, in order that the transformer may be handled without injury to the coils and without disarranging the elements of the core structure.

Figures 1 and 2 of the accompanying drawings are elevations at right angles to each other of a transformer and an inclosing casing constructed in accordance with my invention, the casing being shown in section to disclose the parts of the transformer and the devices for securing it in position.

Referring to the drawings, the device here illustrated comprises an inclosing casing consisting of a tank 1 and a cover 2, a transformer comprising a plurality of core sections 3, 4, 5 and 6, coils 7, a terminal block 8, and holding-in devices 9. The core sections form two members which are disposed in planes at right angles to each other and surround the sides of the primary and secondary windings of the transformer. After the transformer core sections and coils are assembled, they are clamped together from top to bottom (the axes of the coils being substantially horizontal) by a pair of end frames 10 and 11 and bolts 12 that form parts of the holding-in devices. When the

core sections and coils are assembled, the plane of one of the core members is horizontal while the plane of the other is vertical, the end frames being clamped to the outer surfaces of the core members which lie in a vertical plane. The lower end frame 11 is provided with end projections or ears 13 having holes 14 to receive the bolts 12, and foot projections 15 for supporting the transformer when it is outside of the inclosing casing. The upper end frame 10 is provided with bifurcated projections 16 having their outer surfaces 17 beveled to engage corresponding surfaces 18 on clamping blocks 19 which form additional parts of the holding-in device. The upper frame 10 is also provided with ears or end projections 20, which correspond to the projections 13 of the lower end frame 11, and through which the upper ends of the clamping bolts 12 project. The parts of the bifurcated projections 16 which extend upwardly from the ends of the frame are materially separated so that clamping nuts 21 may be screwed upon the ends of the bolts 12 and against the ear projections 20 without engaging these parts. The end frames may thus be clamped together independently of the holding-in devices.

The transformer is supported in the casing by shoulder projections 22 on its side walls, which are engaged by the horizontally disposed core sections 3 and 4, and the core and windings are firmly held in position within the casing by the blocks 19 which are fitted loosely over the upper ends of the clamping bolts 12 and are engaged by clamping nuts 23, which form parts of the holding-in device. The outer side surfaces 24 of the clamping blocks 19 are also beveled and are adapted to engage correspondingly beveled surfaces 25 on the walls of the casing, so that, when the nuts 23 are screwed down against the blocks 19, the transformer tends to center itself and a downward pressure is exerted against the shoulder projections 22.

Inasmuch as various structural modifications may be effected within the scope of my invention, I desire that only such limitations shall be imposed as are indicated in the appended claims.

I claim as my invention:

1. The combination with an inclosing cas-

ing having internal side projections and inclined surfaces, and a transformer comprising an approximately cylindrical winding and horizontally and vertically disposed 5 core sections, the former of which rest upon said internal side projections, core section clamping devices and means coöperating with said devices and said inclined surfaces to clamp the transformer between the side 10 walls of the casing and against the side projections.

2. The combination with an inclosing casing, an approximately cylindrical winding and a plurality of core sections surrounding 15 the sides of the winding and disposed in substantially radial planes, the axis of said winding lying in a horizontal plane, of end plates that engage opposite outer surfaces of two of the core sections, vertical bolts for 20 clamping the end plates together and adjustable blocks coöperating with the clamping bolts for securing the core sections and the winding in position within the casing.

3. The combination with an inclosing cas-

ing, an approximately cylindrical winding 25 so disposed that its axis is horizontal and a plurality of core sections surrounding the sides of the winding and disposed in pairs in radial planes, of end plates engaging opposite outer surfaces of one pair of core sections which lie in a vertical plane, bolts for 30 clamping the end plates together and adjustable blocks having beveled side and bottom surfaces that engage corresponding surfaces on the walls of the casing and on the 35 upper surface of the top plate for securing the core sections of the winding in position, said blocks being provided with holes through which the upper ends of the bolts extend. 40

In testimony whereof, I have hereunto subscribed my name this 27th day of June, 1908.

OTTO SCHAUMBERG.
